(57) **CLAIM**

The ornamental design for a battery case, as shown and described.

DESCRIPTION

FIG. 1 is a front perspective view of our new battery case;
FIG. 2 is a front view thereof;
FIG. 3 is a top view thereof;
FIG. 4 is a right view thereof;
FIG. 5 is a left view thereof;
FIG. 6 is a rear view thereof; and,
FIG. 7 is a bottom view thereof.

The broken line portion of the figure drawings is included to show unclaimed subject matter only and forms no part of the claimed design.
